UNITED STATES PATENT OFFICE.

NICHOLAS H. BORGFELDT, OF NEW YORK, N. Y., ASSIGNOR TO ADOLPH C. SCHUTZ, ADOLPH LEWYN, MAX MARTIN, AND LEVY BROS., ALL OF SAME PLACE.

CIGAR-BUNCHING MACHINE.

SPECIFICATION forming part of Letters Patent No. 349,336, dated September 21, 1886.

Application filed May 10, 1886. Serial No. 201,697. (No model.)

To all whom it may concern:

Be it known that I, NICHOLAS H. BORGFELDT, a resident of New York city, in the county and State of New York, have invented 5 an Improved Cigar Bunching Machine, of which the following is a full, clear, and exact description, reference being made to the accompanying drawings, in which—

Figure 1 is a vertical central section of so 10 much of a cigar-bunching machine as contains my present invention. Fig. 2 is a top view, partly in section, of the same. Fig. 3 is a bottom view of the same, partly in section. Fig. 4 is a detail top view of the lower ring.

15 This invention relates to certain improvements on the cigar-bunching machine which is described in Letters Patent No. 331,676, dated December 1, 1885, and in application for Letters Patent known as Serial No. 179,306, 20 filed October 8, 1885.

The object of the present invention is to simplify the construction of the tobacco-distributing disks which are contained in the main cylinder.

25 In the drawings, the letter B represents the said cylinder, having the discharge chute C. D is the lower disk, which rests on the bottom of the cylinder B, and E the upper disk, which is attached to the shaft F. This shaft F rests 30 on the screw a, so that it can be raised and lowered at will, and this screw has a shoulder, b, which carries a set-screw, d, that rests on the frame A, for the purpose of locking the screw a in any desired position.

35 According to my present invention the lower disk, D, as it has heretofore been called, becomes a mere annulus with radially-projecting wings e, while the upper plate, E, has downwardly-projecting tapering-blocks f, 40 surely attached to its under side near its periphery, said blocks being made concave on their outer sides, as shown in Fig. 3, and

adapted to pass between the blades e e of the lower ring, D. By raising or lowering the shaft F, to which the plate E is rigidly attached by a set-screw, g, or otherwise, the distance between the plate E and the bottom of the cylinder B can be regulated at will, the blocks f dipping to the desired extent into the spaces between the blades e. The nearer 45 the plate E is to the bottom of the cylinder the smaller will be the doses of tobacco that are fed to the chute C.

On the upper side of the plate E is a ring, h, (see Fig. 2,) which reduces the entrance to 50 the openings or cavities that are on the outer sides of the blocks f. Screws or rods j may extend downwardly from the plate E through eyes i in the ring D, for the purpose of better 55 guidance of the plate E during its vertical adjustment. As the ring D is loose, and as the blocks f of the plate E enter between the blades e of the ring D, it follows that the ring D is revolved whenever the plate E is revolved 60 by the shaft F.

I do not in this application claim anything 65 that is claimed in application known as Serial No. 201,696, filed May 10, 1886, by myself and A. C. Schutz for patent for cigar-bunching machine.

I claim—

The ring D, having outwardly-projecting 70 radial wings e e, combined with the plate E, having downwardly-projecting tapering blocks f, and with the vertically-adjustable shaft F, 75 which carries said plate E, and with the cylinder B, and means, substantially as described, for adjusting the shaft, substantially as and for the purpose herein shown and described.

NICHOLAS H. BORGFELDT.
